UNITED STATES PATENT OFFICE.

ALBERT V. GUDE, JR., OF ATLANTA, GEORGIA.

FLOOR OR WALL GROUND.

1,264,505.

Specification of Letters Patent. Patented Apr. 30, 1918.

Application filed January 26, 1917. Serial No. 144,781.

To all whom it may concern:

Be it known that I, ALBERT V. GUDE, Jr., a citizen of the United States, residing at Atlanta, in the county of Fulton and State 5 of Georgia, have invented new and useful Improvements in Floor or Wall Grounds, of which the following is a specification.

This invention relates to floor or wall grounds of the general type disclosed in my 10 co-pending application Serial No. 124,608 wherein the ground comprises a nail receiving block, a portion of adhesive wall-engaging material in which the block is partly embedded, and a metallic keying means associated with the under or inner face of said 15 block and securely engaged and gripped by the adhesive material which also engages and grips said block.

The present invention consists more particularly in the novel construction, as hereinafter described and claimed, of the keying element of a floor or wall ground of the type stated and the novel relation of the said element to the nail receiving block; and the 25 invention has for its principal objects to provide a keying element which can be easily, quickly and certainly applied to the nail receiving block, which requires no nails or other fastenings for its attachment to 30 said block, and which may be made at a minimum of expense.

An embodiment of the invention is illustrated in the accompanying drawings, wherein:—

35 Figure 1 is a sectional view showing the improved ground fitted to a wall or floor.

Fig. 2 is a plan view showing the block and the keying elements of the ground.

Fig. 3 is a sectional view of a slightly 40 modified construction wherein the ground is shown as fitted to a floor or wall.

Fig. 4 is a bottom plan view of the block and keying elements of the construction shown in Fig. 3.

45 Fig. 5 is a sectional view of a further modified construction, showing the ground as fitted to a wall or floor.

Fig. 6 is a plan view of the block and keying elements of the construction shown 50 in Fig. 5.

Similar characters of reference designate corresponding parts throughout the several views.

The ground is shown as applied to a wall 55 or floor A and consists of the nail receiving block 1, the portion of adhesive material 2,

such as plaster of Paris, in which said block is partly embedded and the keying elements 3.

In all cases the block and the keying elements are formed whereby the keying elements may be fitted to, and by virtue of their fitted relation, securely maintained upon, the block; and the relation of the keying elements and the block is such that the adhesive material which grips the under face of the block will also securely grip and engage the keying elements. The keying element includes a bar which extends across the under face of the block and preferably 70 contacts therewith, in which case, the said under face is provided with recesses across which the bar extends whereby portions of the bar will be wholly embedded in the adhesive material filling said recesses. 75

As shown in Fig. 1, the block has a dovetail cross-section and a keying element is arranged at each end thereof, the keying element comprising a frame, preferably of wire, and having a bar 4 which extends 80 transversely across the end face of the block, a bar 5 which extends transversely across the under face of the block, and angular terminal portions 6 which rest against the beveled sides of the block and connect the bars 4 and 5, the portions 6, of course, conforming 85 to, or occupying planes parallel to the planes of, the said beveled sides against which they rest. Where the bar 5 contacts with the under face of the block, as is preferred, said 90 under face is provided with one or more recesses 7 which are preferably in the form of longitudinal grooves extending continuously between the end faces of the block. 95

The fit of the keying elements upon the block is sufficiently close to insure the retention of said elements, against accidental displacement by frictional pressure.

The block with the keying elements fitted thereto, in the manner described, is then 100 partly embedded in the plastic material applied to the wall and the said material engages the under face of the block and fills the grooves or recesses 7, thereby engaging over and securely gripping and retaining 105 the keying elements.

In the modified construction shown in Figs. 3 and 4, the block is of substantially the same form as in Fig. 1. The keying elements, however, are constructed of narrow bars or strips of sheet metal which are provided with angular terminal portions 8 110

to conformably engage over the beveled sides of the block. In this modification the keying elements are not fitted against the ends of the block, as in Figs. 1 and 2, but 5 may be arranged in any desired locations and in any desired number intermediate said ends. If desired, keying elements of the construction shown in Fig. 3 may be employed in addition to and intermediate the 10 keying elements of the construction shown in Figs. 1 and 2.

In the modification shown in Figs. 5 and 6, the block does not have a dove-tail cross section, but, instead, is provided with laterally projecting base flanges 9; and the keying elements, which, as in the construction shown in Figs. 3 and 4, are composed of narrow bars or strips of sheet metal, are provided at their ends with angular terminal portions 10 to conformably engage over said flanges. Except for the variation in the form of the block, the modification shown in Figs. 5 and 6 is similar to that 20 shown in Figs. 3 and 4.

25 It is to be noted that in each of the constructions described the keying elements are arranged in spaced relation whereby the plastic material has free access to the under and side faces of the block for gripping engagement therewith, while at the same time, the said keying elements are, for substantial portions of their length, embedded in and, hence, securely gripped and engaged by said material.

30 I claim as my invention—

1. In a floor or wall ground including a nail receiving block and a portion of adhesive material in which said block is embedded, said block being of greater width in 40 its lower portion than in its upper portion and having its under face provided with recesses, a metallic keying element comprising a relatively narrow bar extending across and adjacent the under face of said block 45 and across the recesses thereof and provided with angular terminal portions which engage over the sides of said block and thereby hold said bar in position.

2. In a floor or wall ground including a 50 nail receiving block and a portion of ad-

hesive material in which said block is embedded, said block being of dove-tail cross-section and having its under face provided with recesses, a metallic keying element comprising a frame formed with a bar which 55 extends transversely across and adjacent the end face of the block, a second bar which extends transversely across and adjacent the under face of the block and across the recesses thereof and angular terminal portions connecting said bars and fitted against the beveled sides of the block.

3. In a floor or wall ground including a nail receiving block and a portion of adhesive material in which said block is embedded, said block being of greater width in its lower portion than in its upper portion, a metallic keying element comprising a frame formed with a bar which extends transversely across and adjacent the end 70 face of the block, a second bar which extends transversely across the under face of the block and is related thereto whereby it may be embedded in and engaged by the adhesive material engaging said under face 75 and angular terminal portions connecting said bars and fitting against the sides of said block to thereby hold said frame in position.

4. In a floor or wall ground including a nail receiving block and a portion of adhesive material in which said block is embedded, said block being of greater width in its lower portion than in its upper portion, a metallic keying element comprising a relatively narrow bar which extends transversely across the under face of the block and is related thereto whereby it may be embedded in and engaged by the adhesive material engaging said under face, said bar 85 being provided with angular terminal portions which engage over the sides of said block and thereby hold said bar in position.

In testimony whereof I have hereunto set my hand in presence of two subscribing 95 witnesses.

ALBERT V. GUDE, JR.
